CHRISTOPHER BALSEY McCUEAN AND BURTON ELLSWORTH MILLER, OF CONNELLSVILLE, PENNSYLVANIA.

CAR-REPLACER.

1,122,973.

Specification of Letters Patent. Patented Dec. 29, 1914.

Application filed June 20, 1914. Serial No. 846,345.

To all whom it may concern:

Be it known that we, CHRISTOPHER B. McCUEAN and BURTON E. MILLER, citizens of the United States, residing at Connellsville, in the county of Fayette and State of Pennsylvania, have invented a new and useful Car-Replacer, of which the following is a specification.

The invention relates to improvements in car replacers.

The object of the present invention is to improve the construction of car replacers and to provide a simple, strong, and comparatively inexpensive car replacer of relatively light construction, equipped with means adapted to clamp the car replacer firmly and securely to a rail, and capable of adjustment to engage rails of different sizes.

20 A further object of the invention is to provide a car replacer of this character in which the means for fastening the car replacer to the rails will be easily operable, and at the same time, permanently connected with the car replacer, so that there will be no liability of the parts becoming separated and lost, whereby the car replacer will always be in condition for instant use.

With these and other objects in view the invention consists in the construction and novel combination of parts hereinafter fully described, illustrated in the accompanying drawing, and pointed out in the claims appended hereto, it being understood that 35 various changes in the form, proportion, size and minor details of construction, within the scope of the claims, may be resorted to without departing from the spirit or sacrificing any of the advantages of the 40 invention.

In the drawing: Figure 1 is a front elevation of a car replacer constructed in accordance with this invention. Fig. 2 is an end elevation of the car replacer, showing 45 the same applied to a rail, the latter being in section. Fig. 3 is a plan view, partly in section. Fig. 4 is a rear elevation of the car replacer, partly in section. Fig. 5 is a transverse sectional view on the line 5—5 50 of Fig. 3.

Like numerals of reference designate corresponding parts in all the figures of the drawing.

In the accompanying drawing, in which 55 is illustrated the preferred embodiment of

the invention, 1 designates a car replacer consisting, preferably, of a hollow casting and comprising inner and outer walls 2 and 3 and a top connecting portion 4. The inner and outer walls 2 and 3 are substantially 60 segmental; the outer wall extends above the plane of the inner wall, and the top portion 4, which is curved longitudinally, is also laterally inclined. The curved top portion, which is substantially arcuate, extends upwardly and inwardly from each end to the center, and it has a slight transverse curvature which extends downwardly and inwardly toward the rail 5, to which the car replacer is secured. When a car wheel is 70 drawn upwardly over the car replacer from either end, it is lifted to a point above the rail, and the lateral inclination of the convex upper face of the car replacer causes the wheel to slide downwardly and inwardly toward the rail, and the car wheel is thereby 75 easily replaced on the said rail.

The hollow construction of the car replacer provides a relatively light construction which is strengthened by transverse 80 webs or flanges 6 arranged within the hollow body of the car replacer at the top thereof and disposed in approximately radial relation. The end webs or flanges are horizontal and provide flat surfaces to rest 85 upon two cross ties, (not shown); the central web or flange is disposed in a vertical position; and the intermediate flanges are arranged at different inclinations, as clearly illustrated in Fig. 4 of the drawing. The 90 end webs or flanges are provided at their lower faces with spurs or pointed projections 7, adapted to be embedded in the cross ties to prevent longitudinal movement of the car replacer. The inner wall of the car 95 replacer is provided at its exterior with a recess 8 forming a lower thin vertical portion and a relatively thick upper projecting overhanging portion 9 extending upwardly and inwardly over the outer bottom flange 100 of the rail and terminating in a vertical plane adjacent to the head of the rail, so that the upper laterally curved wheel receiving face of the car replacer is extended to a point in close proximity to the rail. 105

The inner and outer walls are provided with centrally depending extensions 10 and 11 of approximately rectangular form, adapted to project downwardly between two cross ties and provided with alined openings 110

12 and 13, through which passes a rail engaging bar 14. The bar 14, which is flat, is provided at its inner end with a hook 15 forming a jaw and adapted to engage with 5 the inner bottom flange of the rail. The opening 12 of the extension 10 of the inner wall is enlarged to permit the locking bar 14 to swing upwardly and downwardly sufficiently to engage the hook or jaw 15 with 10 the bottom flange of the rail, and to disengage it therefrom. The bar projects outwardly beyond the outer wall 3 and it is provided in its outer portion with a longitudinal slot 16 for the reception of a wedge 17 15 which engages the exterior face of the outer wall 3 and the outer end wall of the slot 16, whereby the locking bar is drawn into tight engagement with the rail. The slot extends inwardly beyond the inner face of the outer wall 3, and is designed to be of sufficient 20 length to permit the necessary adjustment of the locking bar to enable the car replacer to be applied to rails of different sizes. In order to prevent the locking bar from becoming accidentally separated from the body 25 of the car replacer and being lost, it is equipped with a vertical screw 18 extending through a perforation 19 of the bar 14 and projecting above and below the same a sufficient 30 distance to prevent the bar from being moved inwardly through the inner opening 12. The screw is secured to the locking bar by upper and lower nuts 20 which engage the upper and lower faces of the locking bar. The wedge 17, which has an inclined outer edge and a vertical inner edge, 35 is provided with an arm 21 extending along the exterior face of the outer walls 3 and pivoted to the same by a bolt 22 or other suitable 40 means, to permit the wedge to be swung upwardly and downwardly into and out of engagement with the locking bar. When the wedge is disconnected from the locking bar, it is retained in position for instant 45 use by the pivot of the arm 21. By this construction the car replacer is always in condition for instant use, and may be easily and quickly adjusted to rails of different sizes.

50 What is claimed is:—

1. A car replacer consisting of a hollow body and comprising substantially segmental spaced inner and outer walls, and an arcuate top portion inclined laterally and longitudinally and connecting the inner and outer walls, the said outer wall being vertical and the inner wall being provided in its exterior face with a recess forming a lower relatively thin vertical portion and an upper enlarged 55 projecting portion arranged to overhang the 60

bottom flange of a rail and constituting an extension of the top of the body, said extension permitting the car replacer to be supported by the cross ties beyond the rail.

2. A car replacer including a hollow body 65 comprising inner and outer substantially segmental walls, a substantially arcuate top portion connecting the inner and outer walls at the top of the body, a longitudinal series of webs or flanges connecting the inner and outer walls at the top of the body and disposed substantially radially with relation to the said walls, the end webs or flanges being horizontal to rest upon the cross ties and provided with means for engaging the same. 75

3. A car replacer including a body adapted to be arranged upon the cross ties at the side of a rail and provided with inner and outer depending portions extending below the said rail and having aligned openings 80 located in substantially the plane of the bottom flanges of the rail, the opening of the inner depending portion being enlarged, a locking bar extending through the aligned openings and having an inner rail engaging 85 end, said inner enlarged opening permitting the locking bar to be oscillated to engage it with and disengage it from the rail, means carried by the locking bar and located between the said inner and outer depending 90 portions and projecting above and below the openings to retain the locking bar therein, and means carried by the car replacer and constituting a substantially permanent part 95 thereof for retaining the locking bar in engagement with the rail.

4. A car replacer including a body provided with inner and outer depending portions having aligned openings, a locking bar extending through the openings and provided at its inner end with a rail engaging portion, the outer portion of the locking bar having a slot, a vertical device mounted on the locking bar between the said inner and outer depending portions and projecting 100 above and below the said bar, said device forming a stop to prevent the withdrawal of the locking bar, and a wedge for engaging the slot of the locking bar, said wedge having an arm pivoted to the outer wall of the 105 body and permitting the wedge to swing into and out of the said slot.

In testimony, that we claim the foregoing as our own, we have hereto affixed our signatures in the presence of two witnesses.

CHRISTOPHER BALSEY McCUEAN.

BURTON ELLSWORTH MILLER.
